UNITED STATES PATENT OFFICE.

STEPHAN QUAST, OF CHICAGO, ILLINOIS.

GOVERNOR.

SPECIFICATION forming part of Letters Patent No. 411,056, dated September 17, 1889.

Application filed March 12, 1889. Serial No. 302,940. (No model.) Patented in Germany March 22, 1881, No. 16,159.

To all whom it may concern:

Be it known that I, STEPHAN QUAST, a subject of the Emperor of Germany, residing at Chicago, in the county of Cook and State of Illinois, have invented a new and useful Improvement in Governors, (for which I have obtained German Patent No. 16,159, of March 22, 1881,) of which the following is a specification.

10 My invention relates to an improvement in the class of governors known as "position-governors"—a term employed to designate their manner of regulating an engine by continually changing from one position to another 15 and alternately increasing and diminishing the speed of the engine within a given range.

The primary objects of my improvement are to provide a regulating mechanism wherein the pendulum shall act upon and control the 20 valve, but in which, on the other hand, the latter shall not exert any influence upon the pendulum, and whereby the movement of the mechanism through which it acts on the valve shall be directly proportional to the vertical 25 play of the governor and afford regularity or evenness in the movement of the pendulum.

In the accompanying drawings, Figure 1 shows my improved device in sectional elevation. Fig. 2 is a broken sectional view of the 30 part of the device from or from near the lower end of the screw, the section being taken at right angles to that of Fig. 1; and Fig. 3 is a broken view similar to that presented in Fig. 1 and showing a modification.

35 A, Figs. 1 and 2, is the ordinary rotary spindle, having supported from its upper end, in a usual manner, the pendulum portion B.

C is the weight on the spindle, but loose thereon, so as to be unaffected immediately by 40 its rotary movement and having a sleeve-extension *r* below it around the spindle, and *q* is a collar loosely surrounding the sleeve *r* to permit of its sliding up and down on the latter, and having a circumferential groove *q'*, 45 into which extends the end of the valve-controlling lever *p*, which may be fulcrumed on an arm *o*, extending outward from a frame portion D of the device, which serves also to support other parts hereinafter described.

50 E' is a beveled gear-wheel secured in horizontal position upon the spindle A, near the lower end of the latter, to rotate with it.

F is the driving-shaft, supported on the frame D and carrying vertically a beveled gear-wheel E, meshing with the wheel E', and 55 also with a similar wheel E², loosely surrounding the spindle A above the wheel E', so as not to rotate with the spindle. Each wheel E' and E² has respectively on the opposing faces a flange *n*, the edge of which flanges are 60 provided with clutch-teeth *m*.

G is a sleeve surrounding the spindle and terminating at its lower end in a lateral flange *l*, extending between the flanges *n* of the wheels E' and E², and provided on its upper and 65 lower sides with clutch-teeth *m'* to interlock with those above or below them, in the manner and for the purpose hereinafter described. The parts *n* and *l* thus form clutches or a preferred form of the mechanism for interlocking the screw, hereinafter described, with the driving-shaft and valve-controlling mechanism *p*, as shown in Fig. 1 or in Fig. 3.

The sleeve G is threaded externally toward its upper end to form a screw H, having a 70 diametrically-smaller screw H' inserted into it and loose upon the spindle, but confined against vertical movement between collars *x* and *x'*, which rotate with the spindle. The screw H has a key *g*, and the screw H' a key-sleeve *g'*, in which the key *g* may move up and down. Around the larger section of the screw is a flanged nut *k*, connected from its flange by means of rods *i* with a flanged collar *k'*, loosely surrounding the sleeve *r* toward 85 its lower end, and around the part H' of the divided screw is a flanged nut *h*, connected by means of rods *i'*, extending vertically at right angles to the rods *i*, with laterally-flanged extensions of the collar *g*.

90 The operation is as follows: The wheel E on the rotating driving-shaft, by its permanent engagement with the beveled gear-wheels E' and E², turns the former, and with it the spindle A, in one direction (right or left, depending on the direction of rotation of the driving-shaft) and the wheel E² in the opposite direction. As the load of the engine lightens, producing increase of the speed of the driving-shaft and divergence of the pendulum-balls B, the weight C is raised, and with it, through the sleeve *r*, rods *i*, and nut *k*, the sleeve G, thereby moving over—that is, sliding vertically upon—the screw H', and bring-

ing the teeth on the upper side of the flange l in mesh with the teeth m above it, and causing the divided screw on the sleeve to be revolved in the direction of rotation of the wheel 5 E^2 , and thus turning the stationary screw H' in the nut k and the screw H in the nut h in a direction which causes the nuts to rise and the nut h to raise the collar q , which raising of the latter actuates the lever p to shut to 10 the required extent the valve. (Not shown.) When the engine attains its regular speed, the pendulum, collar k' , and nut k stop rising, and the screw H will follow the clutch-flange n until flange l is disconnected from 15 the flange n . As the speed of the engine gets lower, the pendulum, the collar k' , the nut k , and the screw H move downward, and the clutch-flange l will engage the clutch m' on the lower flange n of the beveled gear 20 E' until the engine again attains its regular speed. Then the pendulum and the parts it carries stop moving downward and the clutch-flange l follows the clutch-flange n until it becomes disconnected. When in the divergence 25 of the pendulum-balls they reach an elevation corresponding with that at which they remain stationary, as meeting the requirements of the engine, the clutch is naturally thrown out of mesh, thereby enabling 30 the pendulum and collar q to remain in their attained positions.

It will be understood that when the lower screw H is moved upward or downward through the medium of the pendulum the 35 key g moves in the key-sleeve g' without producing any effect upon the screw H' , but that as soon as the screw H is turned by engagement between the clutch and a flange n the screw H' will be turned in the same direction. The 40 thread on the screw H is provided to allow the pendulum to move up and down. When the pendulum rises, the screw H will be turned through the engagement with a clutch-flange n and works in the nut k , which is 45 connected through the rods i with the collar k' so long as the pendulum continues to rise. As soon as the pendulum stops to change its position, the clutch-flange l on the screw H disconnects from the clutch-flange n and 50 stops the rotation of the screw H and the vertical movements of the nut k and collar k' .

The screw H' is herein referred to as being stationary in the sense that it has no vertical movement, as has the screw H , inasmuch as 55 the collars x hold it against vertical play; but it does not mean that the screw H' is non-rotary, since it is loose on the spindle and must turn with the turning of the screw H , owing to the provision of the key g' .

60 The modification illustrated in Fig. 3, while substantially like the construction illustrated in Fig. 1, affords an adaption of the invention particularly for controlling slide-valves. To this end a worm-wheel p (corresponding with the lever p in Fig. 1) on a shaft g , connected with the valve (not shown) to be controlled, meshes with a worm-sleeve p' , secured around

a vertical rotary shaft A , which is normally stationary and actuated to turn in one direction or the other as the divergence or convergence of a pendulum (with which the device is connected from a stem e) causes a sleeve r' , carrying the screw H and forming with the latter a part of the shaft or spindle A , to ascend or descend, and thereby produce engagement of the teeth m' on the upper or lower side of the flange l with the respectively adjacent teeth m on the flange n of the gear-wheels E^2 and E' , which are both loose on the shaft. 70 75 80

What I claim as new, and desire to secure by Letters Patent, is—

1. In a governor, the combination, with the pendulum, driving-shaft, and connecting medium between the governor and the valve to be controlled, of a vertically-movable screw H and a vertically-immovable screw H' , both surrounding the governor-spindle and connected to rotate together, and interlocking mechanism actuated by the rise and fall of the pendulum to rotate the screw respectively in opposite directions, and thereby actuate the said connecting medium between the governor and valve to regulate the valve, substantially as described. 90 95

2. In a governor, the combination, with the pendulum, driving-shaft, and connecting medium between the governor and valve to be controlled, of a vertically-movable screw H and a vertically-immovable screw H' , both surrounding the governor-spindle and connected to rotate together, a miter-gear E on the driving-shaft, miter-gears E' and E^2 on the spindle and in mesh with the wheel E , and clutch mechanism actuated by the rise and fall of the pendulum alternately to interlock the screw with the respective miter-gears on the spindle, and thereby turn the screw and produce action upon the said connecting medium to regulate the valve, substantially as 100 105 110 described.

3. In a governor, the combination, with the pendulum, driving-shaft, and connecting medium between the governor and the valve to be controlled, of a vertically-movable screw H and vertically-immovable screw H' , both surrounding the governor-spindle and connected to rotate together, a miter-gear E on the driving-shaft, miter-gears E' and E^2 on the spindle and in mesh with the wheels E and E^2 and provided with clutch-teeth m , and clutch-teeth m' , connected with the screw and extending between the toothed flanges n , whereby the rise and fall of the pendulum alternately interlocks the screw with the miter-gears on the spindle, and by the resultant turning of the screw actuates the said connecting medium to regulate the valve, substantially as described. 115 120 125 130

4. A governor comprising, in combination, a rotary spindle A , supported by a suitable frame D and carrying a pendulum B , a weight C , having a sleeve-extension r loosely sur-

rounding the spindle, a sliding collar *q* on the said sleeve-extension to engage with the lever *b*, leading to the valve to be controlled, a vertically-movable screw *H*, having a key *g*, 5 and a vertically-immovable screw *H'*, having a key-sleeve *g'*, and both loosely surrounding the spindle, a toothed flange *l* on the lower end of the screw *H*, nuts *k* and *h*, respectively surrounding the screws *H* and *H'*, and connected, respectively, with a collar *k'* on the

sleeve-extension *r* and with the collar *q*, miter-gears *E'* and *E²*, surrounding the spindle on opposite sides of the toothed flange *l*, and a miter-gear *E* in mesh with the wheels *E'* and *E²* and actuated by the driving-shaft, 15 substantially as and for the purpose set forth.

STEPHAN QUAST.
